UNITED STATES PATENT OFFICE.

DAVID W. PHILLIPPY, OF KALAMAZOO, MICHIGAN.

WASHING-MACHINE.

No. 927,069.

Specification of Letters Patent.

Patented July 6, 1909.

Application filed June 1, 1908. Serial No. 435,978.

To all whom it may concern:

Be it known that I, DAVID W. PHILLIPPY, a citizen of the United States, residing in the city and county of Kalamazoo, State of Michigan, have invented certain new and useful Improvements in Washing-Machines, of which the following is a specification.

This invention relates to improvements in washing machines.

10 The main objects of this invention are: First, to provide an improved washing machine which utilizes a metal tub of ordinary construction as the main receptacle. Second, to provide in an improved washing machine 15 an inner lining which is effectively supported and may be readily removed, and a structure which can be shipped in the knock-down or nested form. Third, to provide an improved washing machine which may be made of 20 comparatively light material, and one which is, at the same time, very strong and rigid. Fourth, to provide an improved washing machine which in construction and operation is very effective for the purpose.

25 Further objects, and objects relating to structural details, will definitely appear from the detailed description to follow.

I accomplish the objects of my invention by the devices and means described in the 30 following specification.

The invention is clearly defined and pointed out in the claims.

A structure embodying the features of my invention is clearly illustrated in the accompanying drawing, forming a part of this specification, in which,

Figure 1 is a vertical section of my improved washing machine, taken on a line corresponding to line 1—1 of Fig. 2, the 40 agitator and the crank and shaft therefor being shown in full lines. Fig. 2 is a plan-view of my improved washing machine. Fig. 3 is a horizontal section, taken on a line corresponding to line 3—3 of Fig. 1. Fig. 4 45 is an enlarged detail elevation of one of the clamp members. Fig. 5 is a detail vertical section of one of the clamp members, taken on a line corresponding to line 5—5 of Fig. 4. Fig. 6 is a horizontal section, taken on a line 50 corresponding to line 6—6 of Fig. 1, showing the form of the agitator.

In the drawing, the sectional views are taken looking in the direction of the little arrows at the ends of the section lines, and

similar numerals of reference refer to similar 55 parts throughout the several views.

Referring to the drawing, the tub 1 is preferably a common metal washing tub. I provide a cover 2 for the tub which is formed of sheet metal and is provided with 60 a downwardly-projecting annular flange 3 spaced from its outer edge so that the flange projects downwardly within the tub when the cover is resting on the outturned rim 4 of the tub. This flange 3 is preferably angle-shaped in cross section and is secured to the top by turning the edge of the same downwardly and inwardly over the horizontal arm of the flange, as clearly appears in Figs. 1 and 5.

70 The inner wall 5 is formed of a strip of vertically-corrugated sheet metal, the ends of the strip being overlapped, as clearly appears in Fig. 3, and secured together by bolts, as 6. This makes the lining or inner wall 75 adjustable, and also enables its being shipped in the knock-down, or in nested form, if desired,—that is, several inner walls may be nested in their set up form when disconnected from the flange 4. The walls are, therefore, preferably detachably connected to the flange by means of the bolts 7, so that the parts can be readily shipped in disassembled condition to the dealer or user, which 80 results in great economy.

85 The cover is secured to the tub by means of clamps, preferably consisting of the clamp brackets 8, which are angle-shaped and provided with slots 9 in their horizontal arms, which rest on the top of the cover and are 90 secured to the cover by means of the rivets 10 arranged through these slots, so that the brackets can be readily engaged over the rim of the tub, and also to effectively secure the tops to tubs which vary somewhat in 95 size.

On the vertical arms of the clamp brackets, I arrange the eccentric clamps 11 having engaging lips 12 adapted to engage under the rim, thereby effectively securing the cover. These 100 clamp eccentrics are provided with suitable handles, as 13, for convenience in manipulation. The top is provided with a door 14 which is also formed of sheet metal, being secured at one side by means of suitable 105 hinges 15. The door opening is provided with a downwardly and inwardly turned flange 16, which forms an effective door cas-

ing. This also serves to make the top rigid, the advantage of which will appear when the operation of the device is pointed out.

Centrally of the door, I arrange a bearing 5 17 for the shaft 18 of the agitator 19. This bearing 17 is carried by a spider 20, the arms of which extend diagonally of the door, forming rigid braces therefor as well as effective supports for the bearing. On the 10 top side of the door is a thrust bearing 21 against which the bearing member 22 on the crank 23 is adapted to rest when the shaft 18 is in its lower position.

The door is provided with a downwardly 15 and inwardly turned flange 24 adapted to fit in the door casing flange 15, forming an effective support for the door and a comparatively close joint therefor. The door is held in its closed position by means of suitable 20 buttons, as 25, and the cover is also preferably provided with a wringer support 26.

In operation, the cover is secured to the tub, which effectively supports the inner wall in position. The water and the clothes 25 are then introduced through the door, and the door is closed and secured. The shaft is axially movable in its bearings so that it may be drawn up to permit the opening of the door. After securing the door, the agitator is rotated or reciprocated by means of the crank, and this stirs the clothes in the tub and also whirls the water about in the tub, which, striking against the corrugated inner wall, is dashed back against the clothes, 35 thereby causing a complete agitation, not only of the clothes, but of the water in the tub, so that very effective results are secured.

The device has the further advantage of 40 not wearing the clothes as is the case where they are forcibly moved over a rubbing surface.

Having thus described my invention, what 45 I claim as new and desire to secure by Letters Patent is:

1. In a washing machine, the combination with a tub having an outturned rim, of a top 50 adapted to rest on said rim, said top having a downwardly-projecting flange spaced from its outer edge; an inner wall formed of a strip of vertically-corrugated sheet metal detachably secured to said flange on said top, the ends of said strip of sheet metal being overlapped and detachably connected; a plurality 55 of angle-shaped clamp brackets arranged at the edge of said cover, the horizontal arms of said brackets having longitudinal slots therein and being adjustably secured to said cover by rivets arranged through said slots; and eccentric clamps carried by the vertical arms of said brackets adapted to engage under the rim of said tub, for the purpose specified.

2. In a washing machine, the combination with a tub having an outturned rim, of a top 65 adapted to rest on said rim, said top having a downwardly-projecting flange spaced from its outer edge; an inner wall formed of a strip of vertically-corrugated sheet metal secured to said flange on said top; a plurality of angle-shaped clamp brackets arranged at the edge of said cover, the horizontal arms of said brackets having longitudinal slots therein and being adjustably secured to said cover by rivets arranged through said slots; and eccentric clamps carried by the vertical arms of said brackets adapted to engage under the rim of said tub, for the purpose specified.

3. In a washing machine, the combination with a tub having an outturned rim, of a top 80 adapted to rest on said rim; a plurality of angle-shaped clamp brackets arranged at the edge of said cover, the horizontal arms of said brackets having longitudinal slots therein and being secured to said cover by rivets 85 arranged through said slots, whereby said brackets may be adjusted to be engaged over the rim of the tub; and eccentric clamps carried by the vertical arms of said brackets adapted to engage under the rim of said tub, 90 for the purpose specified.

4. In a washing machine, the combination with a tub, of a sheet metal top therefor having a door opening therein, the metal about said opening being turned downwardly and 95 thence inwardly to form a door casing; a sheet metal door having downwardly-turned flanges at its edge adapted to fit said casing; a bearing arranged centrally of said door; a spider secured to the under side of said door 100 whereby the same is braced and said bearing supported; an agitator; and a crank shaft therefor arranged through said bearing.

5. In a washing machine, the combination with a tub, of a removable top for said tub 105 having a downwardly-projecting flange within the tub; an inner wall formed of a strip of vertically-corrugated sheet metal detachably secured to said flange on said top, the ends of said strip forming said wall being overlapped 110 and detachably connected and means for clamping said top to said tub.

In witness whereof, I have hereunto set my hand and seal in the presence of two witnesses.

DAVID W. PHILLIPPY. [L. S.]
